UNITED STATES PATENT OFFICE.

CALVIN A. CAMPBELL, OF MONTREAL, QUEBEC, CANADA.

PAPER-FILE.

SPECIFICATION forming part of Letters Patent No. 371,547, dated October 18, 1887.

Application filed June 1, 1887. Serial No. 239,986. (No model.)

To all whom it may concern:

Be it known that I, CALVIN ALGERNON CAMPBELL, of the city of Montreal, in the county of Hochelaga, in the Province of Quebec, Canada, agent, have invented certain new and useful Improvements in Paper-Files, of which the following is a specification.

The invention relates to that class of paper-files in which the transferring-wires are arched 10 and lock at their points with the receiving-wires, so that the paper may be readily moved from the receiving-wires onto the transferring-wires; and the objects of my invention are, first, to so arrange the receiving and transferring wires that they shall remain rigidly 15 and permanently in position, even when their points are moved apart for the purpose of permitting the removal of the paper; secondly, to connect the index-cover to the wires, so that 20 it may be thrown clear of the receiving-wires without being moved out of place on the transferring-wires, and, thirdly, to provide an improved device for locking the index-cover.

My invention consists, essentially, first, in 25 adapting mechanism by which the points of the receiving-wires are moved toward or from the points of the transferring-wires; secondly, in hinging the index-cover to a plate fitted over the transferring-wires and making slots 30 in the index-cover, so that the said index cover shall be thrown off the receiving-wires without raising its hinged end; and, thirdly, in adjustably connecting to the index-cover a plate having tapered slots made in it to fit over 35 the receiving-wires.

Figure 1 is a perspective view of my improved paper-file. Fig. 2 is an enlarged perspective detail, partially in section, of my receiving and transferring wires with the mechanism for operating the receiving-wires. Fig. 3 is an alternative form of the mechanism shown in Fig. 2.

In the drawings like letters of reference indicate corresponding parts in the different 45 figures.

A are the receiving-wires, and B the transferring-wires. When I make the transferring-wires in pairs, I form them both out of a single piece of wire, as indicated in Fig. 2, and in 50 any case I rigidly attach them to the bed-plate C, which is fastened to the bottom board, D, of the file.

When the receiving-wires are made as shown in Figs. 1 and 3, the said receiving-wires are fastened to the top E of the bed-plate, as indicated. When made in this form, 55 the points of the receiving-wires are separated a sufficient distance from the points of the transferring wires to allow papers to be placed on or removed from the file, and as it is necessary that the space thus left between the points of the wires referred to shall be closed or filled up when the papers are to be moved from the receiving-wires onto the transferring-wires I make the receiving-wires hollow and 60 pass through each receiving-wire a smaller wire, F, which I connect by a lever, G, to the rod H, which I journal in the bed-plate C and provide with a suitable handle or crank, I, located either in the position indicated in Fig. 70 1 or in any other convenient place.

When the two receiving-wires are used, I connect them together by the horizontal rod J and provide two levers G. Thus it will be seen that in order to open or close the space 75 between the point of the receiving-wire and the point of the transferring-wire it is merely necessary to adjust the crank-handle I so as to move the wires F in the direction desired.

A spring, K, attached to the bed plate C, is 80 arranged to act on the rod H, as indicated in Fig. 2, so that the said spring will hold the wires F either against the points of the transferring-wires or below the points of the receiving-wires, accordingly as they may be adjusted by the movement of the crank I. 85

In Fig. 2 the receiving-wires A are connected direct to the rod J, and adjustably support them in sockets L, attached to the bed-plate C, so that the receiving-wires themselves 90 may be adjusted for the same purpose as the wires F. Instead of the socket L, I sometimes steady the receiving-wires A, when made as shown in Fig. 2, by a smaller wire inserted into the hollow receiving-wires A and rigidly 95 fastened to the top E.

As shown in Fig. 3, the top E is made so that it may be removed from the bed-plate C, and in order that the receiving-wires may be moved with it I form a fork on the end of the 100 lever G, as indicated.

With the view of locking the top E in position I attach a projecting finger or fingers, b, to the side of the bed-plate C, and on the bot-

tom of the top E, I attach a finger, *d*, bent so that it may be slipped below the finger *b* when the top E is placed in position, and in order to lock the said top I attach to it the sliding latch *e*, formed so that one portion of it will project below the stationary part of the top of the bed-plate C.

It will be noticed that the index-cover M is hinged to the plate N, which is pierced, so that 10 it will fit over the transferring-wires B. It will also be seen that slots *g* are made in the index-cover M, so that the said cover may be thrown back over the transferring-wires without moving the plate N.

15 In Fig. 1 I show my lock for securing the index-cover in position. This lock consists of a plate, O, adjustably connected to the cover M, and having tapered slots *h* made in it, so as to fit onto the receiving-wires A, the said 20 slots being tapered, so that they will grip the receiving-wires A when the plate O is adjusted in the direction required.

It will of course be understood that the plate N may be made in two parts when used with 25 a double-arched file; or, in other words, lugs with holes in them to fit over the transferring-wires may be hinged to the index-cover, which I consider as an equivalent for the plate N which I have shown.

30 Among the advantages of my invention I may mention that by making the receiving-wires vertically adjustable I am enabled to utilize them for the purpose of punching holes in the papers to be filed. In order to accomplish this end, I have merely to make punches at the points of either the receiving-wires or the transferring-wires, suitable gages being provided, if desired, for the purpose of guiding the paper in proper position between the 35 points of the receiving and transferring wires. By hinging the index-cover to a plate or lug fitting over the transferring-wires and by making the slots *g* the index-cover has merely to be thrown back, where it will remain, leaving both hands of the party using the file free to handle the papers.

I am aware that it has been proposed to

construct a letter-file wherein the transferring-wires were so connected to mechanism that when it was desired to file any papers thereon 50 they could be first adjusted vertically and then thrown back to allow of the papers being placed on the rigid receiving-wires, and do not seek to cover such construction. I deem it important that my transferring-wires be rigid, 55 and my wires A in Fig. 2 or F in Figs. 1 and 3 be adjustable and in a direct vertical line only.

What I claim as my invention is—

1. In a letter-file, a rigid arched transferring-wire, combined with a wire moving in a 6c vertical guide, and mechanism for imparting to said wire a vertical movement upward to close the space between the adjacent ends of said wires, as set forth.

2. In a letter-file, an arched transferring-wire, in combination with a receiving-wire vertically adjustable and connected by the lever G to the rod H, journaled in the bed-plate C, arranged substantially as and for the 7c purpose specified.

3. In a letter-file, a pair of arched transferring-wires formed in one piece and rigidly fastened to the bed-plate C, in combination with the vertically-adjustable receiving-wires 75 A, connected to the rod H by the lever G, substantially as and for the purpose specified.

4. An index-cover, M, having slots *g* made in it to fit over the receiving-wires A, in combination with a plate, N, fitted over one end 8c of said cover, hinged to the index-cover M and fitted over the transferring-wires B, substantially as and for the purpose specified.

5. The combination, with receiving-wires, of a plate, O, lengthwise adjustably connected 85 to the index-cover M, and having tapered slots *h* to fit over the receiving-wires, substantially as and for the purpose specified.

Toronto, May 26, 1887.

CALVIN A. CAMPBELL.
